UNITED STATES PATENT OFFICE.

THOMAS LOUIS JONES, OF HAMBURG, GERMANY.

COMPRESSED-AIR MOTOR.

No. 874,771.

Specification of Letters Patent.

Patented Dec. 24, 1907.

Application filed June 17, 1907. Serial No. 379,483.

To all whom it may concern:

Be it known that I, THOMAS LOUIS JONES, a citizen and resident of Hamburg, in the German Empire, have invented a certain 5 new and useful Compressed-Air Motor, of which the following is a specification.

This invention relates to a compressed air motor and its object is to construct a motor of this kind which runs perfectly quietly and 10 without jerks.

Motors driven by compressed air known heretofore which work similar to a steam-engine are only operated by thrusts and varying expansions and therefore can only run 15 evenly, if provided with a fly-wheel which consumes part of the power. The new motor, which is shown in the drawing does away with these drawbacks.

Figure 1 is a side view partly in section 20 and Fig. 2 a vertical section drawn to the line 2 of Fig. 1.

The motor consists of a casing containing a high pressure chamber A and a low pressure chamber B, arranged side by side and separated by an imperforate partition E which contains an air tight bearing D for a motor-shaft C. Within the high pressure chamber A the shaft C is provided with a number of radially disposed tubes a and curved tubes b 25 in equal number are also attached to the shaft within the low pressure chamber B. Each tube b is in communication with one of the tubes a by a longitudinal passage c in the shaft C. The tubes b, which are all bent in 30 the same direction as may be clearly gathered from Fig. 1 are considerably longer than the tubes a so that each pair of tubes a, b together with their connecting passage c form communicating tubes having arms of 35 unequal lengths. The chamber A which is made air tight where the shafts projects through the outer wall by a stuffing box D¹ is provided with an inlet l on the top for the compressed air and a water inlet s¹ at the bottom. The chamber B has an air-outlet e at 40 the top and a water outlet s at the bottom.

On supplying compressed air by the tube l to the chamber A, which is previously filled with water or some other liquid nearly to the 45 height of the shaft C, the air will also rush into the chamber B by way of the tubes a, passages c and tubes b, which on account of their curvature will begin to move in the direction of the arrow W, thus turning the 50 shaft C in the same direction.

Owing to the fact that the tubes a are by

such rotation temporarily immersed in the water or other liquid contained in the chamber A, small quantities of liquid and compressed air alternately pass into the tubes a and by the way of the passages c into the tubes b, through which they flow out into the chamber B. The quantities of liquid owing to their greater weight, act with greater force on the walls of the tubes b than the compressed air, thus increasing the power of 60 the shaft C.

In order to obtain as uniform a rotation as possible it is advisable to maintain the level of the water or other liquid in the vessel A 65 invariably at the same height and this is attained by means of a float f which at a given height of the liquid causes a valve f to close the inlet s¹. The supply may be furnished either by a piston pump or by a centrifugal 70 pump, not shown, mounted on the shaft or otherwise in operative connection with the same. This pump may be so arranged that it forces the liquid running out of the chamber B from the pipe s into the pipe s¹ and 75 from here back into the chamber A. In order to avoid the tubes a and b striking the water with great force, the spaces between the tubes may be filled up, so that disks are formed having radial passages. The pressure of highly compressed air or gas can be utilized to a better advantage by combining 80 two or more motors one behind the other.

Instead of using the apparatus as a motor it may also be used as an air compressor. In 85 this case the shaft C is driven by any suitable motor preferably in the direction of the arrow W¹. The quantities of water rushing through the tubes or passages b by the centrifugal force create a sucking action in the passages 90 c and in the tubes or passages a; thus the air out of the chamber A is forced into the chamber B and compressed air may be taken from the tube e. The chamber A may be open to 95 the air on top and the tube l removed. Also 100 the pump between the tubes s and s¹ may be dispensed with and instead of in the chamber A the float valve may be arranged in the chamber B.

To obtain a greater pressure than is possible by using one of these compressors of a certain diameter and with a limited number of revolutions, several of these compressors can be combined one behind the other.

I claim:

1. A compressed air motor comprising a casing having a high pressure chamber and a

- low pressure chamber provided respectively with an inlet and an outlet, a rotatable shaft in said chambers, a plurality of short tubes mounted on the shaft in the high pressure chamber and a plurality of longer tubes mounted on the shaft in the low pressure chamber communicating with the short tube.
2. A compressed air motor comprising a casing having a high pressure chamber and a low pressure chamber provided respectively with air and water inlets and air and water outlets, a rotatable shaft in the chambers provided with longitudinal passages, a plurality of short radial tubes on the shaft in the high pressure chamber communicating with the passages, and a plurality of longer curved tubes on the shaft in the low pressure chamber communicating with the short tubes through said passages.
3. A compressed air motor comprising a casing having two chambers, a rotatable shaft projecting into said chambers having longitudinal passages connecting the chambers, radial tubes attached to the shaft at both ends of the passages, and disks of different diameter on each set of tubes forming radial passages.
4. A compressed air motor comprising a casing having two chambers, a rotatable shaft projecting into said chambers having longitudinal passages reaching from one chamber to the other and radial tubes attached to the shaft at both ends of the passages one set of tubes being shorter than the other, the longer tubes being bent in one direction within the plane of the set of tubes.
5. A compressed air motor comprising a casing, an imperforate partition in the casing forming a high pressure chamber and a low pressure chamber, a shaft rotatably mounted in the partition having a plurality of longitudinal passages connecting the chambers, a plurality of short radial tubes on the shaft in the high pressure chamber communicating with the passages and a plurality of longer curved tubes on the shaft in the low pressure chamber communicating with the short tubes through said passages.
6. A compressed air motor comprising a casing, an imperforate partition in the casing forming a high pressure chamber and a low pressure chamber, said high pressure chamber having an air inlet in the top and a water inlet in the bottom and the low pressure chamber having an air-outlet in the top and a water outlet in the bottom, a shaft rotatably mounted in the partition extending into both chambers having a plurality of longitudinal passages, a plurality of short radial tubes on the shaft in the high pressure chamber communicating with the passages and a plurality of longer curved tubes on the shaft in the low pressure chamber communicating with the tubes through the passages.
